DESIGNATOR FOR PNEUMATIC CARRIERS

Filed August 18, 1925

Inventor.
Frank Holdsworth,
by Roberts Roberts & Cushman
Atty's.

UNITED STATES PATENT OFFICE.

FRANK HOLDSWORTH, OF EASTWOOD, NEW YORK, ASSIGNOR TO THE LAMSON COMPANY, OF SYRACUSE, NEW YORK, A CORPORATION OF MASSACHUSETTS.

DESIGNATOR FOR PNEUMATIC CARRIERS.

Application filed August 18, 1925. Serial No. 50,936.

This invention pertains to carriers employed in pneumatic dispatch systems and more particularly to group designators for such carriers useful for purposes of ready classification. Such group designators are particularly useful in making a primary division into groups of all of the carriers in the system by causing one group to present a different appearance from any angle of view from carriers belonging to other groups, it being understood that any usual designating means, for example, numerals or letters are or may be provided for distinguishing individual carriers of a group.

The principal object of the present invention is to provide means readily applicable to a carrier of any usual type but particularly to a carrier having non-removable heads, for example, a so-called "take-apart" carrier, which will distinguish that carrier from another carrier not belonging to its group. A secondary object is to provide a designator of durable and inexpensive character, light in weight, and of material obtainable in a variety of brilliant and permanent colors.

In the accompanying drawings, in which a preferred embodiment of the invention is illustrated by way of example.—

Fig. 1 is a side elevation of a take-apart carrier embodying the present invention;

Fig. 2 is a side elevation of the same carrier with its inner and outer shells separated and axially aligned, and with my novel designator device interposed between them;

Fig. 3 is a bottom plan view of the designator device shown in Fig. 2;

Fig. 4 is a fragmentary diametral section through the upper end of the lower carrier shell shown in Fig. 2, with the designator ring applied thereto;

Fig. 5 is a fragmentary side elevation to small scale showing the invention embodied in a message carrier of well-known type;

Fig. 6 is a view similar to Fig. 5 but showing an alternative arrangement; and

Fig. 7 is a fragmentary side elevation to small scale of a cash or charge carrier of usual type having the present invention embodied therein.

Referring to the drawings, the numeral 1 designates the inner cylindrical shell of the carrier, said shell having a head 2 at one end thereof. In this type of carrier the head is permanently attached to the shell, for example by means of rivets.

The outer shell 3 is also provided with a head 4 non-removably secured to one end and is provided with the usual driving washer 5 adapted to make air-tight contact with the inner surface of the pneumatic transmission tube.

The inner shell 1 is furnished with an elongate access opening 6 which is adapted to register with a corresponding access opening 7 in the outer shell when the shells are turned to the proper relative angular position.

The end 7 of the shell 1 is provided with an axially directed channel 8 extending outwardly from the opening 6 to the end of the shell. This channel may conveniently be formed by pressing the metal of the shell inwardly during the process of manufacture.

The channel 8 forms a passage for the head of a stop pin 9 projecting inwardly from the wall of the outer shell 3 near the head end of the latter. When the parts are assembled the head of this stop pin 9 engages the edge 10 of the aperture 6 of the inner shell and thus prevents relative axial movement of the shells except when the shells are so relatively positioned that the head of the pin may move axially along the channel 8.

Preferably the inner end of the opening 6 is widened out at each side to form recesses 11 and 12 respectively for the reception of the pin 9 so that the shells may be turned in one direction to bring the apertures 6 and 7 into exact registry or in the opposite direction completely to close the carrier.

Preferably the outer shell is provided with an opening 13 in its wall which may be surrounded by an outwardly projecting raised flange 14, thus providing a pocket for the reception of an index slip 15 of the usual character. This slip may be inserted within the pocket when the shells are separated and is retained in position by engagement with the outer surface of the inner shell.

In accordance with the present invention I provide a designator ring 16 which is adapted to fit over the open end of the outer shell 3 as indicated in Fig. 4. This ring 16 is circumferentially continuous and of distinctive external appearance. For example it may have a distinctive color or surface pattern. When color is relied upon to give the distinctive appearance I find that celluloid is a desirable material from which to make the ring since it can be colored very

readily, is light in weight, tough and durable, and may readily be given the desired shape and size.

This designator ring while fitting snugly over the end of the shell 3 is readily removable when the shells are separated so that if worn or broken it may be replaced or when desired it may be interchanged for a ring of another color or appearance.

10 To hold the designator ring closely adjacent to one of the heads of the carrier so that the head may form a protective overhanging flange for the ring, and so that the ring may not interfere with the access openings, I provide stop means to prevent axial movement of the ring relatively to the body of the carrier. A convenient way of forming suitable stop means consists in turning in the edge of the ring to provide a radially directed flange 17. This flange bears against the outer end 18 of the shell 3 and is clamped between the edge 18 of the shell and the overhanging head 2 of the inner shell so that axial movement of the ring is prevented.

As the inner shell 1 must telescope within the outer shell 3, it is essential that the flange 17 be no wider in a radial direction than the thickness of the shell 3 and I prefer to make this flange slightly less than the limiting width in order that the opening 19 defined by the inner edge of the flange may be of sufficient diameter to permit ready entry of the inner shell without special care upon the part of the user.

While I have shown the designator ring as applied to the outer shell, I contemplate that under some circumstances it might possibly be applied to the inner shell, the outer shell being cut away to receive it and expose it to view. Under such circumstances it might be necessary to constrict the open end of the inner shell to afford space for the reception of the designator ring.

45 In Fig. 5 I have shown the present invention applied to a message carrier of usual type, this message carrier comprising tubular body portion 20 provided at one end with the flaring skirt 21 and at its other with the head 22 having the driving washer 23.

The carrier is provided with the usual rotary selecting ring 24 having an opening 25 to exhibit a selected distinguishing numeral upon the outer surface of the carrier shell. 55 In this case my improved designator ring 16 is fitted snugly about the ring 24, the narrow inwardly directed radial flange 17 of the ring 16 engaging the edge of the ring 24, such flange being substantially no wider radially than the thickness of the ring 24. In this case the ring 16 is furnished with an opening 27 registering with the opening 25 so that the numerals upon the body of the carrier may be exhibited.

65 In Fig. 6 a carrier of the same type is

shown, but in this case the designator ring 16, while being mounted on the ring 24, is arranged in reverse relation as compared with that shown in Fig. 5. That is to say, in the latter figure the designator ring 16 is adjacent to the carrier head, while in Fig. 6 the designator ring 16 is spaced from the head. This latter arrangement is permitted by the fact that the radial flange 17 is no thicker than the thickness of the ring 24 so that the composite ring comprising the parts 16 and 24 can readily be slipped lengthwise of the carrier body.

In Fig. 7 I have shown a carrier of ordinary type, for example a cash carrier, having a body portion 25, a head 26, and my improved designator ring 16 encircling the body 25 at a point closely adjacent to the head. In this case the radial flange fits within the angle between the end of the carrier body and the face of the head and thus prevents axial movement of the ring 16.

While the inwardly directed flange 17 is desirable in most cases, I contemplate that such flange may be dispensed with if other and equivalent means be provided for securely attaching the ring to the carrier body or other part with which it is associated. For example such an annulus or ring unprovided with a flange, may be cemented or riveted in place or may merely be made of a diameter such that when forced over the cylindrical carrier part with which it is associated its frictional engagement therewith is sufficient to prevent displacement.

I claim:

1. A designator device for a take-apart pneumatic carrier having a body portion consisting of separable, telescoping cylindrical shells, each provided with a non-removable head, said designator comprising a continuous removable ring of colored celluloid fitting over the open end of the outer shell and having a radial stop member engaging the edge of the shell, said stop member being arranged to permit free telescoping of the shells relatively to one another.

2. In combination with a pneumatic despatch carrier having a body portion comprising concentric relatively rotatable telescoping cylindrical shells longitudinally separable in one position of relative angular adjustment, each shell having a non-removable head, a continuous ring of distinctive appearance encircling the body portion of the carrier at a point closely adjacent to one of the fixed heads, said ring being provided with means for preventing longitudinal movement thereof relatively to the body portion of the carrier when the parts of the latter are assembled, said ring being removable from the carrier when the shells are separated.

3. In combination with a pneumatic despatch carrier having a body portion com-

prising concentric relatively rotatable telescoping cylindrical shells longitudinally separable in one position of relative angular adjustment, each shell having a non-removable head, a continuous ring of uniform and distinctive color and appearance throughout its entire circumferential extent fitting snugly over the outer shell near the open end of the latter, said ring having an inwardly directed radial flange engaging the edge of said outer shell, the flange being of less radial width than the thickness of the wall of said shell, the head of the inner shell overhanging said ring when the carrier is assembled and thereby affording protection to the ring.

4. A designator device for a pneumatic carrier having a cylindrical body portion, said designator comprising a continuous ring of distinctive appearance fitting over the end of the body portion and having an inwardly directed radial flange engaging the end of said body portion, said flange being of a radial width not greater than the thickness of the wall of said body portion.

5. In combination with a pneumatic despatch carrier comprising coaxial separable parts, means normally retaining said parts in assembled relation, a ring of distinctive appearance encircling and snugly fitting the outer surface of one of said parts, said ring being always exposed to view, the ring be-

ing removable from the part which it encircles only when the said coaxial parts are separated.

35 6. A designator device for a pneumatic despatch carrier having a head and a cylindrical member, said designator device comprising a distinctively colored annulus adapted snugly to embrace the said cylindrical element of the carrier and to abut an element of the head, said annulus being removable from the part which it embraces only when the head and said cylindrical part are separated.

40 7. A designator device for a pneumatic carrier, comprising a colored cylindrical ring, having a narrow, radially and inwardly turned annular flange at one end, said flange having a radial width of a dimension of the order of its own thickness and forming a relatively rigid stop member.

45 8. A designator device for a pneumatic carrier comprising a colored celluloid annulus adapted to fit snugly over a cylindrical part of the carrier, said annulus having an inwardly directed radial flange adapted to engage the end surface of said cylindrical part, said flange being substantially no wider in a radial direction than the material of which said part is made.

50 Signed by me at Syracuse, New York,
this 20th day of July, 1925.

FRANK HOLDSWORTH.
